BURGLAR ALARM

Filed March 13, 1937

FIG. 1

FIG. 2

FIG. 4.

UNITED STATES PATENT OFFICE

2,187,194

BURGLAR ALARM

Clifford M. Chapman, Indianapolis, Ind., assignor of one-third to Avada Storm and two-thirds to Russell R. Wilkinson, both of Indianapolis, Ind.

Application March 13, 1937, Serial No. 130,651

5 Claims. (Cl. 177—329)

This invention relates to an alarm system or apparatus particularly adapted for use as an automatic burglar alarm but also useful as a manually operable alarm for banks and the like.

3 The invention may also be used as a combined fire and burglar alarm or as a fire alarm only.

One object of the invention is to provide an alarm which, when operated either automatically or manually, warns the occupants of a building of impending danger or leads an intruder to believe that he is under fire from armed guards or other protectors of the premises. To this end there is provided a firearm which is automatically fired repeatedly when the apparatus is operated and which preferably discharges either blank cartridges or gas shells. When the device has been properly placed in a concealed location, the intruder is unable to detect the source of the firing and his natural impulse under the circumstances is to depart as speedily as possible. To add to the effectiveness of the apparatus, an audible alarm device is preferably added together with mechanism operating the alarm device when a predetermined number of shots have been fired or a predetermined length of time has expired.

Other objects and features of the invention will be readily understood from the accompanying drawing and the following description and claims:

30 Fig. 1 is a plan view of the apparatus assembled in a suitable container. Fig. 2 is a sectional view on the line 2—2 of Fig. 1. Fig. 3 is a wiring diagram showing the connections within the apparatus and the connections to an external alarm circuit and a remote alarm device, and Figure 4 is a detail fragmentary sectional view through the bracket and showing the manner of connecting the trigger therewith.

In the preferred form of the invention shown 40 by way of illustration in the drawing, there is provided a suitable box or container 10 having a removable cover 11 and within which there are secured a plurality of cells 12 forming a battery for the supply of electric current, a relay 13, a terminal socket 14, having external openings for the reception of plugs 15, 16 and 16a of the usual household type and a base plate 17 on which there are mounted the principal mechanical parts of the apparatus.

45 The base 17 has secured thereto an electric motor 18, having a worm 19 on its rotor shaft meshing with a worm gear 20 which is in turn secured to a horizontal shaft 21 journaled in bearing brackets 22 supported on the plate 17. The shaft 21 has secured to its opposite end a striker

in the form of a bar 23 carrying rollers 24 at each end. A repeating revolver 25 has its trigger 26 secured by welding, sweating or otherwise to a stud 27 which is fixedly secured to a bracket 28 carried by the plate 17. In the operation of this part of the apparatus, the energizing of motor 18 rotates the striker in the direction of the arrow in Fig. 2 and repeatedly brings the rollers 24 into contact with the butt of the revolver. Since the trigger 26 is fixed, the body of the revolver rotates about the internal pivot of the trigger and the resulting relative motion is the same as when the trigger is manually pressed. The muzzle of the revolver is therefore raised into line with an opening 29 in the casing 10 and is fired in that position each time one of the rollers 24 strikes the butt. Preferably, blank cartridges are used, or gas shells may be substituted.

For stopping the motor 18 and initiating the operation of an external alarm device, there is provided a commutator or limit switch consisting of a drum 30 of insulation material carrying a semicircular contact segment 31 on its periphery and a contact plate 32 on one face. The plate 32 is electrically connected to the segment 31 at one end and protrudes at its opposite end, as best seen in Fig. 3, sufficiently to engage a contact finger 33 which is normally out of contact with other parts of the commutator. A second contact finger 34 engages the drum 30 or segment 31, depending upon the position of the drum. Both fingers are mounted upon an insulation block 35 carried by the base 17 and are insulated from each other.

The drum 30 is freely mounted on a stud 36 which is secured to the upper end of an arm 37 pivotally mounted on a bracket 38 secured to the plate 17. A grooved friction pulley 39 of insulation material is secured to the drum 30 and rotates therewith. Said pulley engages a friction pinion 40 carried by the shaft 21. A tension spring 41 is secured to the end of stud 36 and to one of the brackets 22 and draws the arm 37 about its pivotal mounting to maintain frictional contact between pulley 39 and pinion 40 for rotating the drum 30 when the motor 18 is in operation.

The relay 13 is of a common form in which an electromagnet 42, when energized, draws a pivotally mounted armature 43 about its pivotal mounting 44 against the action of a tension spring 45. When said electromagnet is energized, the upper end of the armature is pressed against an insulated stop 46 and when said

magnet is deenergized the spring 45 draws the armature against a contact member 47.

Referring now to the wiring diagram, one terminal of battery 12 is connected to a main control switch 48 by conductor 49, which leads through socket 14 and plug 16a. The main switch 48 is preferably a key operated switch and is used to disconnect the apparatus when not in use and to connect it during periods of service. The opposite terminal of switch 48 is connected to the relay contact 47 and to the electromagnet 42 by conductor 50 via plug 16a and socket 14. The opposite terminal of electromagnet 42 is connected to the external alarm circuit 51 by conductor 52 via socket 14 and plug 15. The external circuit 51 is connected through plug 15, socket 14 and conductor 53 to the opposite terminal of the battery 12. The external alarm circuit may be of the usual normally closed form connected to doors, windows or other strategic portions of the premises to be protected in such a manner that an intruder tampering with an important object therein will open the circuit. As long as the circuit is complete and main switch 48 is closed, the electromagnet 42 is energized and there is no contact between members 43 and 47. Once the external circuit is broken, the electromagnet is de-energized and contact is immediately made between said members.

30 The armature 43 is connected to contact plate 32 preferably by a ground connection through plate 17 and 31, and stud 36 which is in electrical contact with plate 32. This connection is shown diagrammatically in Fig. 3 by the equivalent conductor 54. The contact finger 34 is connected to the motor 18 by conductor 55. The motor is connected to battery 12 by a branch of conductor 53. By means of the wiring just traced, the motor circuit is completed to operate the apparatus when it is set with finger 34 engaging segment 31 and when contact 43-47 is closed by the breaking of the external alarm circuit. When the apparatus is made ready for use, the commutator is preferably set manually in the position shown in Fig. 3. The completion of the 43-47 contact, therefore, starts the motor which runs until the commutator has made substantially a half revolution and the 31-34 contact has been broken. During this period, the revolver will be fired repeatedly. Preferably, the time of motor operation is sufficient to permit the revolver to discharge all of its cartridges.

55 The finger 33 is connected to an external alarm device 56 which may be a bell, buzzer or visual signal located on the protected premises or at a position remote therefrom. This connection is through conductor 57 via socket 14 and plug 16. The alarm device is connected to battery 12 through conductor 58, a thermostatic timer 59 and a branch of conductor 53 via plug 16 and socket 14. When the 31-34 contact is broken, at the end of the motor operation, the 32-33 contact is closed to complete the following circuit: 12, 49, 50, 47, 43, 54, 32, 33, 57, 56, 58, 59, 53, 12. This circuit causes the alarm device to operate and in ordinary circumstances, it will continue to operate until the thermostatic timer 59 opens the circuit at the end of a predetermined length of time. This timer may be of a common

form which embodies a snap switch opened by action of a thermostatic element at the end of a predetermined time and thus prevents a second operation of the alarm until the switch has been reset. It may also be of a common intermittent 5 type which provides intermittent operation of the alarm until its circuit is opened by means of the main switch 48 or otherwise. In either case, the purpose of the timer is to prevent the nuisance of a continuously sounding alarm after the need for 10 the same has passed and before the circuits may be manually opened. In installations where a continuous alarm may not be regarded as a nuisance, the timer may be omitted. Obviously, other forms of electrical timers than the thermostatic form may be used—for example, the ratchet type of timer associated with an audible signal described in Weaver Patent No. 1,179,987.

20 The foregoing specification describes a preferred form of the invention, the details of which may be varied between wide limits without departing from the scope thereof as defined by the appended claims. For example, the normally closed external circuit herein described may be replaced by the normally open circuit usually used with manually controlled alarms. To adapt the device for such a circuit, it is only necessary to reverse the positions of the insulated stop 46 and the contact member 47. Thermostatic switches may also be included in the external 30 circuit and the apparatus then becomes a combined fire and burglar alarm. The term "fire-arm" as used in the claims is not to be taken as limiting the invention to the use of standard revolvers, rifles or other arms suitable for other purposes, but is intended to include any form of device capable of exploding a cartridge or gas bomb in a realistic manner.

35 The invention claimed is:

1. In an alarm apparatus means for mounting a firearm, with its trigger in a fixed position, a striker adapted to strike said firearm and to move the same relative to the trigger for discharging the same, and means for actuating said striker.

2. In an alarm apparatus, means for mounting a firearm with its trigger in a fixed position, a rotating striker adapted when rotated to repeatedly strike the firearm to move the same relative to its trigger for repeatedly discharging the same, and means for rotating the striker.

3. In an alarm apparatus, means for mounting a firearm with its trigger in a fixed position, a rotating striker adapted when rotated to repeatedly strike the firearm to move the same relative to its trigger for repeatedly discharging the same, a motor for rotating said striker, and means for energizing said motor.

4. In an alarm device, a support, a firearm, means on said support to rigidly secure the trigger of the firing arm to said support, and means for rocking said firearm upon its trigger.

5. In an alarm device, the combination with a repeating firearm to be fired upon each retraction of its trigger, of a support, means maintaining said firearm in rocking position upon said support with its trigger affixed thereto, and a motor to rock said firearm.

CLIFFORD M. CHAPMAN.
